UNITED STATES PATENT OFFICE.

HUBERT D. CLARK, OF COLUMBUS, OHIO.

GRAVE-VAULT.

1,230,115.

Specification of Letters Patent. Patented June 19, 1917.

Application filed March 31, 1916. Serial No. 88,152.

To all whom it may concern:

Be it known that I, HUBERT D. CLARK, a citizen of the United States, residing at Columbus, in the county of Franklin and State 5 of Ohio, have invented certain new and useful Improvements in Grave-Vaults, of which the following is a specification.

My invention relates to grave vaults and is particularly directed to the improvement 10 of a lock designed to be used in connection with the parts of a grave vault for holding them permanently in their locked position after they have been made to incase the re- mains.

15 My invention is particularly directed to simplifying these locks and to also make them occupy as small space as possible and at the same time bearing in mind a construction which will render them proof against 20 tampering by unauthorized persons.

The preferred embodiment of my invention is shown in the accompanying sheet of drawings, in which similar characters of reference designate corresponding parts, 25 and in which:

Figure 1 is a perspective of a vault shown in section, my improved type of lock being also shown in section,

Fig. 2 is an enlarged cross sectional view 30 taken through my improved type of lock,

Fig. 3 is a horizontal section taken through the structure shown in Fig. 2,

Fig. 4 is a transverse section taken on line 4—4 of Fig. 2, and,

35 Fig. 5 is a view in perspective of a pin used by me for holding the parts in their inoperative position during shipment.

In these several views, the top or hood is shown at 1 and the base is designated by the 40 reference numeral 2. The hood comprises a top, sides and ends as is usual, and the sides and ends flare outwardly as is shown at 3 and these flares are then bent inwardly as at 4 and given a slight upturn as shown at 5.

45 This flared portion of the hood is designed to coöperate with the locks carried by the base to be presently described, to hold the two sections in their locked position. The base itself comprises a top plate 6 whose 50 marginal portions are all bent down as is shown at 7 and then out as shown at 8 to form a seat for the inturned portions 4 of the hood.

In order to prevent the ends of the flat 55 sections from warping out of shape, I have

located my locking structure in the extreme end portions of the base. In this manner, the locking bolt is effective at each corner and thereby prevents these corner portions from warping. The locking structure itself 60 comprises latch bolts 9 each provided with a tongue portion 10 which projects through cut out portions 11 in the vertical walls 7 of the base. The upper surface of each of these tongues is curved slightly as is shown at 12, 65 while their under surfaces 13 are straight, this arrangement being resorted to so that when the hood is placed in position, it will force the latch bolts rearwardly and after the hood has assumed its operative position 70 to permit the projection of the bolts, the straight under surfaces will prevent removal of the top. In order to shift these latch bolts automatically upon the assumption of the proper position of the hood, I 75 have formed each latch bolt with a horizontally disposed cut-out or hollowed-out portion 14 in which is located the coil spring 15. One end of each of these springs is made to bear against the vertical wall 16 found in 80 each latch bolt, while the rear end of each of these springs bears against the portion 17 of Z-shaped clips 18. The leg 19 of each of these clips is rigidly secured to the vertical end wall 7 of the base, while the other leg 85 20 lies in such position with respect to the open side of the cut-out portion 14 as to form an inclosure or housing for preventing the shifting of the spring 15. It will be noted that the vertical wall 16 against which 90 the opposite end of each spring bears is provided with a central center projection 21 for holding the spring in its centered position. In order to render the operation of the bolt more frictionless, I have provided the upper 95 and lower portions of each of the latch bolts with wearing surfaces 22 and 23 arranged to project slightly beyond the level of the remainder of the body portion of the latch bolt. The under wearing surface 22 of each 100 of these bolts, also serves as a stop shoulder engaging the vertical portion 7 of the base beneath the cut-out portion 11. I have also provided the upper surface 6 of the base with a plurality of apertures 24 corresponding in number with the number of latch bolts. Each of the latch bolts is also provided with an aperture as is shown at 105 25 and when it is desired to render these latch bolts inoperative, they may be retracted 110

against the tension of the springs 15 and held in such retracted position by the insertion of the pins as illustrated at 26 and as shown in detail in Fig. 5. Fig. 2 shows the 5 extended position of the latch bolts in full lines and the retracted position in broken or dotted lines. The space below the aperture 25 in each of the latch bolts is also hollowed out as is shown at 27 to lighten each of the 10 latch bolts and also to permit a space into which the pin 26 may project and not encounter the spring 15. Each of these latch bolts is then incased within a housing such as is shown at 28. These housings are all sub- 15 stantially L-shaped, although the two edge portions 29 and 30 are provided with flanges of a width sufficient only to permit welding of the housing to the base. These L-shaped housings coöperate with the vertical walls 20 7 of the base to completely house each of the latch bolts. The rear of these housings are also closed as is shown at 31 and in this manner it is absolutely impossible to render the latch bolts inoperative when once they have 25 assumed their locking position after the hood is in the position shown in Fig. 1.

From the foregoing description, taken in connection with the accompanying sheets of drawings, it will be apparent that I have 30 provided a very efficient type of grave vault

lock and also that this lock may be made at comparatively small cost.

What I claim, is:

A grave vault comprising a top member, a base member whose marginal portions are 35 bent down substantially at right angles, said marginal portions being provided with a series of cut outs, and latch bolts carried by said base member and arranged to engage the top member, said latch bolts being de- 40 signed to pass through said cut outs, a de- pending lug on said bolts arranged to en- gage the edge of said cut outs to form a stop limiting the outward movement of the bolts, said bolts having a horizontally disposed cut 45 out portion through a substantial portion of their lengths, a spring located in each of said cut out portions and arranged to bear on one end of its respective bolt, and a Z- 50 shaped clip extending into each of said cut out portions and rigidly carried by one of said members against which the opposite ends of said springs bear.

In testimony whereof I affix my signature in presence of two witnesses.

HUBERT D. CLARK.
